UNITED STATES PATENT OFFICE.

JOHN O. PIERPOINT, OF PANA, ILLINOIS, ASSIGNOR OF ONE-HALF TO JOHN J. PIERPOINT, OF PANA, ILLINOIS.

APPARATUS FOR MANIPULATING GLOBES

Application filed May 17, 1924. Serial No. 714,041.

To all whom it may concern:

Be it known that I, JOHN O. PIERPOINT, a citizen of the United States, residing at Pana, in the county of Christian and State 5 of Illinois, have invented a new and useful Apparatus for Manipulating Globes, of which the following is a specification.

The invention relates to apparatus for manipulating electric light bulbs located at 10 remote and relatively inaccessible places with a view to the mounting thereof into their sockets or the removal thereof from their sockets, either in whole or broken state, for replacement.

15 The invention generally has for its object to provide apparatus of the class stated which is more simple and economic to manufacture and more easily operable for accomplishing the intended purposes than apparatus of like character heretofore produced.

In its more detailed nature, the invention seeks to provide apparatus of the class described which embodies particular structural features by the utilization of which the general objects above related are accomplished and which provide a structure particularly light in weight, compact, and easy to operate and control through sustained 25 use, the said structural features being so constructed and cooperatively arranged as to also provide a telescopic arrangement and other details permitting a great range of operative application.

30 35 The invention further comprehends features of construction and arrangement rendering more compact and positive of action the rotary motion transmitting agencies and globe clamping devices and reducing 40 stresses and strains thereof to the minimum, thus greatly reducing wear and effectively preventing all tendency of such parts to bind or become inoperative.

With the above, and other objects in 45 view, the invention still further resides in those novel details of construction, combination and arrangement of parts, all of which will be fully described, then be particularly pointed out in the appended claims, reference being had to the accompanying drawings, in which:

Figure 1 is a side elevation of the invention.

Figure 2 is a plan view of the invention, the manipulating head adjustment range 55 being shown at a single adjusted position of the telescopic sections.

Figure 3 is a fragmentary longitudinal section of the crank or operating end of the 60 apparatus.

Figure 4 is a detail cross section taken on the line 4—4 on Figure 3.

Figure 5 is a detail cross section taken on the line 5—5 on Figure 3.

Figure 6 is an enlarged detail sectional 65 view illustrating the connection of the operating crank to the driving shaft end.

Figure 7 is an enlarged detail longitudinal section of the invention taken through the position of the telescopic section screw 70 lock member.

Figure 8 is an enlarged detail longitudinal section of the globe manipulating head end of the apparatus.

Figure 9 is a view similar to Figure 8, 75 the section being taken through a plane at right angles to that on which Figure 8 is taken, and illustrates an angle adjusted position of the head end.

Figure 10 is a detail cross section taken 80 on the line 10—10 of Figure 8.

Figure 11 is a detail view, partially in section, of a globe base removing attachment.

Figure 12 is a detail cross section taken 85 on the line 12—12 on Figure 8.

Figure 13 is a detail cross section taken on the line 13—13 on Figure 8.

Figure 14 is a detail perspective view of 90 one of the transmission gears.

Figure 15 is a detail perspective view of one of the globe gripping finger member attachments.

In the drawings, in which like numerals of reference indicate like parts in all of the figures, 1 indicates the main housing tube section and 2 the main driving shaft section which is hollow and square in cross section for a purpose that will later be 95 apparent.

The main housing tube section 1 is joined, by the U shaped frame portion 3, secured to the end thereof by the split clamp head 4, to the angle supporting arms 5, which are in turn secured to the securing head 6 carried by the said U shaped frame and also 100 105

to the bow shaped supporting or rest member 7, in the manner illustrated in Figures 1 and 2 of the drawings.

The U shaped frame portion 3 serves to accommodate the positioning of the substantially U shaped operating crank member 8, one end of which is secured to the turning head 9, which is mounted upon the projecting end of the main driving shaft section 2 pin-connected thereto as at 10 to cause the said shaft section to rotate with the crank. The other end of the operating crank has suitable rotatable bearing, as at 11, in the securing head 6, see Figure 3.

A telescopic housing tube 12 is provided which is of a dimension for freely sliding within the main housing tube section 1 so as to be telescoped thereinto for purpose of adjustment, see Figures 1, 2 and 7. The outer end of the main housing tube section 1 is provided with a taper threaded portion 13 which is split at intervals, as at 14, so that when the internally taper threaded screw lock member 15 is screwed tightly 25 home upon the threaded portion 13, the split ends of the said tube section 1 will be forced into tight frictional engagement with the telescopic tube section 12 to tightly secure the same to its adjusted position.

It will be readily understood by reference to the figures just above mentioned, that by reason of providing the telescopic sections and the means for locking the same, the housing of the apparatus may be extended or retracted to any desired adjustment within the limits controlled by the dimensions of the said telescopic parts, thus making it possible to greatly vary the range of use of the invention.

Naturally, by reason of providing the telescopic sections, means must also be provided for longitudinally adjusting the drive shaft mechanisms, and for this purpose I have provided a hollow square driving shaft section 16 telescoped within the main driving shaft section 2. By reason of providing the telescopic sections 2 and 16, the drive shaft may be longitudinally extended in accordance with the housing sections and by reason of the said shaft sections being square, rotation thereof is as readily effected in extended as well as in contracted positions.

Upon the outermost end of the telescopic drive shaft section 16 is mounted a crown gear member 17, by reason of having the sleeve 18 thereof secured upon the said shaft and in a manner for causing the said crown gear member to rotate with the said shaft section. The said sleeve 18 of the crown gear member provides suitable bearing in the outermost end of the telescopic housing tube section 12.

Thus far, I have described the driving shaft sections. It should be understood that

the driven shaft and globe gripping elements are cooperative with the driving shaft features to be driven thereby, the power transmission devices causing the driving shaft sections to cooperate with the said driven shaft and gripping mechanisms being such as will permit a great range of angular adjustment of the relation of the driven shaft with the said driving shaft sections. To accomplish this purpose, I provide a second crown gear member 19 positioned for meshing with the above mentioned crown gear member 17, the said second named crown gear member having the sleeve portion 20 thereof pin secured as at 21 to the sleeve member 22 which in turn has the outer end thereof pin-secured as at 23 to the driven shaft section 24.

A pivot head 25 is secured upon the outermost end of the telescopic housing tube section 12 and the said head is provided with extended apertured pivot ears 26. A similarly shaped pivot head is mounted upon the sleeve portion 20 of the crown gear member 19 between the shoulder formed by that member and the shoulder formed by the adjacent end of the sleeve 22 in such a manner that the crown gear member 19 is freely rotatable in the said head member, longitudinal movement thereof being prevented by shoulder engagement, as explained. The second pivot head member 27 is provided with extended pivot ears 28 which have internally threaded apertures adapted to cooperate with the apertures of the ears 26 of the pivot head 25 to receive the threaded ends of the wing head pivot screws 29 which are passed through the apertures of the said ears 26 and threaded into the threaded apertures of the ears 28. It will be observed that the position of these ears is slightly to the side of the breaking axis of the meshing crown gear members so as to permit arcuate adjustment of the driven shaft and the gripping members, on that particular plane, through the range of adjustment generally indicated in Figure 2 of the drawing, it being understood that this plane of movement may be adjusted to any point around the axis of the housing members by loosening the screw lock member 15 and axially turning the telescopic housing tube section 12 within the main housing tube section 1 to the desired adjustment. Thus the driven shaft and gripping head may be universally adjusted through the arc of adjustment indicated in the figure mentioned, the manner of meshing of the gears being indicated in Figure 9 of the drawings.

Upon the outermost end of the driven shaft section 24 is secured a fixed cylindrical head 30. A slidably or movable head 31 is slidably mounted upon the said driven shaft and has the free end thereof shaped

to abut the fixed head when in the normal or gripper finger closed position, and being provided with an extended abutment head 32, shaped to include an annular groove-way 33 and adapted to be spring acted upon to hold the movable head member 31 to the normal position stated. The normal groove-way 33 serves to accommodate the mounting of the cross head end 34 of the spring-compressing gripper finger actuating stirrup 35, the cross head being mounted in a manner for surrounding the said annular grooveway and for effecting longitudinal movement of the slideable head in opposition to the action of the spring 36 which is coiled about the driven shaft section 24 between the cups 37, one of which abuts the outermost end of the sleeve 22, the other the head 32, see Figures 8 and 9.

20 The sleeve 22 is provided with an opposing pair of longitudinal slots 38 through which pass the cross pin 39 which is connected to the free ends of the stirrup 35, as shown.

25 Operating links 40 are pivoted at 41 in the bifurcated extensions 42 of the slideable head 31 and as at 43 in the bifurcated extension 44 of the individual finger carrying arms 45 pivoted at 46 upon the fixed head 30 in a manner for providing an annular space 47 surrounding the said head.

30 Each of the individual carrying arms 45 is provided with a pair of apertures 48 adapted to removably receive the securing ends 49 of the globe gripping fingers 50 which are each bent up from a piece of stout wire and suitably covered with rubber or leather to prevent fracture of the gloves being manipulated. One of the gripping finger members is illustrated in detail in Figure 15 of the drawings, and it should be understood that the securing ends 49 are spring spread so that when they are drawn together and inserted into the receiving apertures 48 they will be retained by friction and also that the said gripper fingers may be made of various sizes for effectively engaging varied sizes of globes, by reason of being readily demountable from the carrying arms.

35 It will be observed by reference to Figures 8, 9 and 13, that the cross pin 39 has an apertured and enlarged head portion 51 which is slideable within the sleeve 22, the said aperture serving to accommodate the passage of the gripper finger operating cable 52 and to serve as an abutment for the head 53 secured upon the end thereof and designed to engage the pin for effecting a pull action upon the stirrup 35 against the action of the coil spring 36. This cable 52 passes axially through the housing and drive sections and at that point at which the cable passes through the crown gear members 17 and 19, the same is surrounded by a stout

coil spring 54 which serves to protect the same against frictional engagement when the parts are adjusted to positions similar to that illustrated in Figure 9 of the drawings, thus permitting the cable to efficiently function through all positions of the apparatus without danger of unusual wear due to friction.

40 A cable pulling gripper finger actuating lever 55 is pivoted at 56 to the front arm of the operating crank 8 and a pulley 57 is mounted upon the said lever, as at 58, for the purpose of receiving the cable 52 as it passes out of the adjacent end of the driving shaft section 2, and a suitable windlass or spool 59 for taking up the length of the cable in accordance with the adjusted position of the apparatus, is also mounted upon the lever, through the medium of the stirrup connection 60. A cross shaft 61 passes through the spool and the securing stirrup, and the said shaft has its opposite ends threaded for receiving the thumb or wing nuts 62 which may be loosened to permit free rotation of the spool to wind on or pay out the cable as may be necessary, or may be tightened to secure the said spool to fixed position after the length of the cable has been so adjusted. The spool has the flanges thereof knurled as at 63 so that they may be readily hand turned to effect the paying out or winding in of the cable, as stated, and the said lever 55 is extended beyond the connection of the spool 59 so as to constitute a handle portion 64.

45 Thus, it will be observed, by reference to Figures 1 and 3 of the drawings, that the lever 55, the pulley 57 and spool 59 move as a unit and, being pivoted to the crank member 8, the whole of the structures just stated rotate with that crank. Thus, it will be observed as the operator grasps the handle portion 64 of the lever and swings the same on the pivot, as indicated in the said Figure 3 of the drawings, longitudinal pull will be exerted upon the cable, also that when the crank 8 is turned the lever 55, pulley 57, spool 59, shaft sections 2 and 16, crown gear members 17 and 19, and the remainder of the mechanisms carried thereby will be rotated in unison so that no stresses or strain on the parts will be set up such as would induce breakage or quick wear.

50 In Figure 11 of the drawings is illustrated the broken globe manipulating attachment, which includes the broken base engaging bit portion 65, which is in the nature of a case hardened steel sleeve having the outer end shaped to provide the gripping bit, and which is pin connected as at 66 to the wooden insulating section 67 in turn pin connected as at 68 to the metal tube or sleeve 69 slotted as at 70 and of a dimension for being readily insertable into the space 47 surrounding the head 30 with the said slots engaging the

5 pivot pins 46. By providing this member and constructing the same to be readily mountable and removable to and from co-operative relation with the apparatus, a means is provided for effectively removing broken globe bases, it being necessary only to rotate the crank member 8 to the left to effect this operation.

10 An operator desiring to use the apparatus would first ascertain the position of the globes to be manipulated, and adjust the length of his apparatus by manipulation of the screw lock member 15 in the manner hereinbefore stated to extend or retract the telescopic housing sections 1 and 12. This extension or retraction of the housing sections would naturally extend or contract the square telescopic driven shaft sections 2 and 16 accordingly.

15 20 By then resting the bow shaped supporting member against his body, probably at the waist line, and grasping the lower end of the main housing tube section 1 to hold the device firmly, the operator would grasp the operating crank 8 with the free hand and rotate the same to effect rotation of the driven shaft and cooperative elements in the manner hereinbefore described, after having grasped the handle portion 64 and swung 25 30 the lever 55 on its pivot 56 to effect the necessary pull on the cable 52 for spreading the gripping fingers 50 and again releasing the same to allow the spring to force the said fingers tightly against the globe so that 35 40 when rotation is imparted to the elements, as just stated, the said globe will be either screwed into or out of its socket, as the case may be.

In the foregoing, I have disclosed a particularly compact and efficient apparatus which will effectively accomplish the purpose for which the same is designed, which is particularly light in weight and in which the parts are so cooperatively constructed and arranged that wear and strain thereon are reduced to the minimum and in which all of the parts of the device are effectively housed, thus protecting all of the parts against breakage and wear and contributing to 45 50 longevity of the apparatus.

From the foregoing description, taken in connection with the accompanying drawings, it is thought that all of the novel details of description, the manner of arrangement and the advantages of my invention will be readily apparent to those skilled in the art to which it relates.

What I claim is:

1. In apparatus of the class described, 60 opposing globe gripping elements, a hollow driving shaft, a hollow driven shaft telescoped into the driving shaft, means to impart rotation to the shafts, and means passing through said shafts and connected with 65 said gripping elements for manipulating the

gripping elements for the purposes specified.

2. In apparatus of the class described, opposing globe gripping elements, a driving shaft, a driven shaft telescoped into the driving shaft, means to impart rotation to the shafts, levers for manipulating the gripping elements for the purposes specified and a cable connecting the levers and passing axially through the shafts. 70

3. In apparatus of the class described, 75 opposing globe gripping elements, a main square hollow driving shaft section, a telescopic square hollow driving shaft section, means connecting the shaft sections in rotative relation with the gripping elements, 80 means for imparting rotation to the shaft sections, levers for manipulating the gripping elements for the purposes specified, and a cable connecting the levers and passing axially through the square hollow shaft sections. 85

4. In apparatus of the class described, 90 opposing globe gripping elements, a main square hollow driving shaft section, a telescopic square hollow driving shaft section, 95 means connecting the shaft sections in rotative relation with the gripping elements, means for imparting rotation to the shaft sections, levers for manipulating the gripping elements for the purposes specified, a cable connecting the levers and passing axially through the square hollow shaft sections, telescopic housing sections, and means for securing the housing sections at adjusted positions. 100

5. In apparatus of the class described, 105 opposing globe gripping elements, a main square hollow driving shaft section, a telescopic square hollow driving shaft section, 110 means connecting the shaft sections in rotative relation with the gripping elements, means for imparting rotation to the shaft sections, levers for manipulating the gripping elements for the purposes specified, a cable connecting the levers and passing axially through the square hollow shaft sections, and a winding spool for regulating the cable length according to the adjustment of the telescopic shaft sections. 115

6. In apparatus of the class described, 120 opposing globe gripping elements, a main square hollow driving shaft section, a telescopic square hollow driving shaft section, 125 means connecting the shaft sections in rotative relation with the gripping elements, means for imparting rotation to the shaft sections, levers for manipulating the gripping elements for the purposes specified, a cable connecting the levers and passing axially through the square hollow shaft sections, a winding spool for regulating the cable length according to the adjustment of the telescopic shaft sections, telescopic housing sections, and means for securing the housing sections at adjusted positions. 130

7. In apparatus of the class described, opposing globe gripping elements, a driving shaft; a driven shaft telescoped into the driving shaft; means to impart rotation to the shafts; levers for manipulating the gripping elements for the purposes specified; and a cable connecting the levers and passing axially through the shafts; said shaft sections, said gripping elements, and 10 said levers and cable being connected to rotate in unison.

8. In apparatus of the class described, opposing globe gripping elements; a main square hollow driving shaft section; a telescopic square hollow driving shaft section; means connecting the shaft sections in rotative relation with the gripping elements; means for imparting rotation to the shaft sections; levers for manipulating the gripping elements for the purposes specified; a cable connecting the levers and passing axially through the square hollow shaft sections; a winding spool for regulating the cable length according to the adjustment of 20 the telescopic shaft sections; the said shaft sections, said gripping elements, said levers, said cable and winding spool being connected to rotate in unison; telescoping housing sections; and means for securing the 25 housing sections at adjusted positions.

9. In apparatus of the class described, opposing globe gripping elements, a main square hollow driving shaft section, a telescopic square hollow driving shaft section, 30 means connecting the shaft sections in rotative relation with the gripping elements, levers for manipulating the gripping elements for the purposes specified, a cable connecting the levers and passing axially 35 through the square hollow shaft sections, a crank for imparting rotation to the shaft sections, one of the said levers being pivoted to the said crank, and a winding spool mounted upon the lever pivoted to the crank for regulating the cable length according to 40 the adjustment of the telescopic shaft sections.

10. In apparatus of the class described, opposing globe gripping elements, telescopic shaft sections for imparting rotation to the gripping elements, telescopic housing sections for housing the shaft sections, a U-shaped frame portion secured to one housing section, and a U-shaped crank secured to 45 one shaft section and rotatable on an axis aligning with that of the shaft sections for rotating the same.

11. In apparatus of the class described, opposing globe gripping elements, telescopic shaft sections for imparting rotation to the gripping elements, telescopic housing sections for housing the shaft sections, a U-shaped frame portion secured to one housing section, a U-shaped crank secured to 55 one shaft section and rotatable on an axis

aligning with that of the shaft sections for rotating the same, and connections including a cable passing axially through the shaft sections for manipulating the gripping elements.

70

12. In apparatus of the class described, opposing globe gripping elements, telescopic shaft sections for imparting rotation to the gripping elements, telescopic housing sections for housing the shaft sections, a U-shaped frame portion secured to one housing section, a U-shaped crank secured to one shaft section and rotatable on an axis aligning with that of the shaft sections for rotating the same, connections including a cable passing axially through the shaft sections for manipulating the gripping elements, and a lever pivoted to the crank and to which the cable is connected to be pulled thereby.

75

13. In apparatus of the class described, opposing globe gripping elements, telescopic shaft sections for imparting rotation to the gripping elements, telescopic housing sections for housing the shaft sections, a U-shaped frame portion secured to one housing section, a U-shaped crank secured to one shaft section and rotatable on an axis aligning with that of the shaft sections for rotating the same, connections including a cable passing axially through the shaft sections for manipulating the gripping elements, a lever pivoted to the crank and to which the cable is connected to be pulled thereby, and a winding spool for receiving the cable to adjustably secure the end thereof to the lever as stated.

80

14. In apparatus of the class described, opposing globe gripping elements, telescopic shaft sections for imparting rotation to the gripping elements, telescopic housing sections for housing the shaft sections, a U-shaped frame portion secured to one housing section, a U-shaped crank secured to one shaft section and rotatable on an axis aligning with that of the shaft sections for rotating the same, connections including a cable passing axially through the shaft sections for manipulating the gripping elements, a lever pivoted to the crank and to which the cable is connected to be pulled thereby, a winding spool for receiving the cable to adjustably secure the end thereof to the lever as stated, and means for holding the spool securely fixed and for permitting free rotation thereof to secure the cable in a manner permitting adjustment of its length according to adjustment of shaft and housing sections.

85

15. An apparatus of the class described, a driving shaft, a driven shaft, means connecting the shafts in a manner permitting angular adjustment, a fixed head on the driven shaft, a slideable head on the driven shaft, means normally forcing the slideable

- against the fixed head, arms pivoted to the fixed head and link connected to the slidable head, a stirrup for moving the slidable head abnormally, a cable for moving the stirrup, and gripping elements removably carried by the pivoted arms.
16. In apparatus of the class described, telescopic housing sections, telescopic driving shaft sections, a driven shaft, means connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup, and gripping elements removably carried by the pivoted arms.
17. In apparatus of the class described, telescopic housing sections, telescopic driving shaft sections, a driven shaft, means connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup and passing through the driven shaft sections and the shafts' connecting means, and gripping elements removably carried by the pivoted arms.
18. In apparatus of the class described, telescopic housing sections, telescopic driving shaft sections, a driven shaft, means connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup and passing through the driven shaft sections and the shafts' connecting means, gripping elements removably carried by the pivoted arms, and means surrounding the cable at the point of passage through the shafts' connecting means for protecting the same.
19. In apparatus of the class described, telescopic housing sections, telescopic driving shaft sections, a driven shaft, means connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup and passing through the driven shaft sections and the shafts' connecting means, gripping elements removably carried by the

pivoted arms, and a coil spring surrounding the cable at the point of passage through the shafts' connecting means for protecting the same.

20. In apparatus of the class described, telescopic housing sections, telescopic driving shaft sections, a driven shaft, crown gears connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup, gripping elements removably carried by the pivoted arms, and a winding spool for receiving the cable to regulate the length thereof according to the adjustment of the said telescopic sections. 70

21. In apparatus of the class described, telescopic housing sections, telescopic driving shaft sections, a driven shaft, crown gears connecting the shafts in a manner permitting angular adjustment, a fixed head on the driven shaft, a slidable head on the driven shaft, means abnormally forcing the slidable against the fixed head, arms pivoted to the fixed head and link connected to the slidable head, a stirrup for moving the slidable head abnormally, a cable for moving the stirrup, gripping elements removably carried by the pivoted arms, a winding spool for receiving the cable to regulate the length thereof according to the adjustment of the said telescopic sections, a crank for rotating the shaft sections, and a lever for pulling the cable and for carrying the winding spool. 85

22. In apparatus of the class described, telescopic housing sections, telescopic driving shaft sections, a driven shaft, crown gears connecting the shafts in a manner permitting angular adjustment, a fixed head on the driven shaft, a slidable head on the driven shaft, means normally forcing the slidable against the fixed head, arms pivoted to the fixed head and link connected to the slidable head, a stirrup for moving the slidable head abnormally, a cable for moving the stirrup, gripping elements removably carried by the pivoted arms, a winding spool for receiving the cable to regulate the length thereof according to the adjustment of the said telescopic sections, a crank for rotating the shaft sections, a lever for pulling the cable and for carrying the winding spool, and cross bolt and wing nut connections for releasably rotatably securing the said spool. 105

23. In apparatus of the class described, telescopic housing sections, telescopic driving shaft sections, a driven shaft, crown gears connecting the shafts in a manner permitting angular adjustment, a fixed head on

the driven shaft, a slidable head on the driven shaft, means normally forcing the slidable against the fixed head, arms pivoted to the fixed head and link connected to the slidable head, a stirrup for moving the slidable head abnormally, a cable for moving the stirrup, gripping elements removably carried by the pivoted arms, a winding spool for receiving the cable to regulate the length thereof according to the adjustment of the said telescopic sections, a crank for rotating the shaft sections, a lever for pulling the cable and for carrying the winding spool, cross bolt and wing nut connections for releasably rotatably securing the said spool, a U-shaped frame for accommodating the position of the crank, and a bow shaped body rest.

24. In apparatus of the class described, 20 a driving shaft, a driven shaft, means connecting the shafts in a manner permitting angular adjustment, a fixed head on the driven shaft, a slidable head on the driven shaft, means normally forcing the slidable 25 against the fixed head, arms pivoted to the fixed head being provided with gripper element mounting apertures and being link connected to the slidable head, a stirrup for moving the slidable head abnormally, a cable for 30 moving the stirrup, and gripping elements having ends removably insertable into the apertures of the pivoted arms.

25. In apparatus of the class described, 35 a driving shaft, a driven shaft, means connecting the shafts in a manner permitting angular adjustment, a fixed head on the driven shaft, a slidable head on the driven shaft, means normally forcing the slidable against the fixed head, arms pivoted to the 40 fixed head being provided with gripper element mounting apertures and being link connected to the slidable head, a stirrup for moving the slidable head abnormally, a cable for 45 moving the stirrup, gripping elements having ends removably insertable into the apertures of the pivoted arms, the said ends being spring spread so as to necessitate frictional engagement in the apertures when contracted and inserted thereinto.

50 26. In apparatus of the class described, telescopic housing sections, telescopic driving shaft sections, a driven shaft, crown gears connecting said driven shaft with one of said driving shaft sections in a manner

permitting angular adjustment, opposing globe gripping elements and means passing through said shafts and gears and connected with said gripping elements to operate the same.

27. In apparatus of the class described, 60 a driven shaft, a fixed head on the driven shaft, a slidable head on the driven shaft, means normally forcing the slidable head against the fixed head, arms pivoted to the fixed head and link connected to the slid- 65 able head, a stirrup for moving the slidable head abnormally, a cable for moving the stirrup, and gripping elements removably carried by the pivoted arms.

28. In apparatus of the class described, 70 a driven shaft, a fixed head on the driven shaft, a slidable head on the driven shaft, means normally forcing the slidable against the fixed head, arms pivoted to the fixed head being provided with gripper element 75 mounting apertures and being link connected to the slidable head, a stirrup for moving the slidable head abnormally, a cable for moving the stirrup, and gripping elements having ends removably insertable into the 80 apertures of the pivoted arms.

29. In apparatus of the class described, 85 a driven shaft, a fixed head on the driven shaft, a slidable head on the driven shaft, means normally forcing the slidable against the fixed head, arms pivoted to the fixed head being provided with gripper element 90 mounting apertures and being link connected to the slidable head, a stirrup for moving the slidable head abnormally, a cable for moving the stirrup, gripping elements having ends removably insertable into the apertures of the pivoted arms, the said ends being spring spread so as to necessitate frictional engagement in the apertures when 95 contracted and inserted thereinto.

30. In apparatus of the class described, 100 a shaft, arms pivotally mounted at one end of said shaft, a slidable head mounted on said shaft and connected with said arms, means normally forcing said slidable head towards said arms, a member for moving said slidable head abnormally, a lever and a connection between said lever and said slid- 105 able head moving member for operating the same, and gripping elements removably carried by said pivoted arms.

JOHN O. PIERPOINT.
